UNITED STATES PATENT OFFICE

2,170,109

FORMING WIRE SUPPORT FOR PAPER MACHINES

Earl E. Berry, Beloit, Wis., assignor to Beloit Iron Works, Beloit, Wis., a corporation of Wisconsin

Application December 15, 1937, Serial No. 179,863

3 Claims. (Cl. 92—44)

This invention relates to table roll structure for supporting traveling forming wires of paper making machines and includes deflector lips on the journals for the table rolls to prevent water 5 from being thrown back through the wire by the rotating table rolls.

More specifically the invention relates to small diameter table rolls for supporting Fourdrinier forming wires and bearing supports or journals 10 for said rolls having laterally extending deflector lips adjacent the tops of the rolls to prevent the rolls from throwing liquid back through the forming wire.

In my copending applications Serial No. 55,753 15 filed December 23, 1935, now U. S. Patent No. 2,111,833 and Serial No. 80,762 filed May 20, 1936, now U. S. Patent No. 2,111,835 I have described and claimed small diameter table rolls and attendant mechanism for supporting traveling forming wires. These small diameter rolls 20 are journaled in bearing supports throughout their entire lengths and extend transversely under the upper run of Fourdrinier forming wires for carrying the forming wires and paper web or stock thereon. Since the small diameter table rolls rotate in the bearing supports at high speeds during normal operation of the paper making machine there is a tendency for the 25 ascending sides of the rolls to pick up water draining through the forming wire and throw this water by centrifugal force back through the wire, thereby disturbing the fiber formation and resulting in the production of paper having uneven thickness and fiber arrangement. There 30 is also a tendency for the descending side of one roller to throw water against the ascending side of the next roller thereby adding to the fiber disturbance.

According to the present invention I now provide 35 deflector lips on the journals or bearing supports for the small diameter table rolls. These deflector lips extend laterally outward from the ascending sides of the table rolls and define flat surfaces adjacent the tops of the rolls over which the forming wire passes. The forming wire, 40 however, is not supported by these flat surfaces but is carried entirely by the rolls.

I am aware that the use of rectangular bars scraping the under side of a forming wire for 45 wiping off a film of water from the wire is known. However, these bars as heretofore used have been also used as supports for the wire and, as is obvious, will rapidly wear away the under side of the wire. In installations where the bars are 50 used in combination with table rolls, the same

are disposed between the table rolls in spaced relation therefrom and cannot function to prevent the rolls from throwing water back through the wire.

The improvement provided by this invention 5 therefor includes the use of a table roll journal to form a deflector lip on the ascending side of a table roll thereby making it impossible for the table rolls to throw water back through the forming wire.

It is then an object of this invention to provide 10 table roll journals with deflector lips extending throughout the length of the table rolls adjacent the ascending side of the rolls.

A further object of this invention is to provide 15 table roll structure for paper making machines wherein table rolls are rotatably mounted in journals coextensive with the length of the rolls and wherein one side of the journals has an integral deflector lip adjacent the tops of the rolls. 20

A further object of this invention is to prevent 25 table rolls from throwing water back through the forming wire of a Fourdrinier paper making machine.

Another object of this invention is to provide 30 bearing supports for small diameter table rolls with enlarged lips at the tops thereof on the ascending sides of the rolls.

Other and further objects of this invention will 35 become apparent to those skilled in the art from the following detailed description of the annexed sheet of drawings.

On the drawing:

Figure 1 is a broken diagrammatic view of the forming part of a Fourdrinier paper making 35 machine showing the upper run of the Fourdrinier wire supported on table rolls journaled in bearing supports according to this invention.

Figure 2 is an enlarged vertical cross-sectional view taken through the upper run of the forming wire shown in Figure 1 and illustrating the 40 table roll structure according to this invention supporting the forming wire.

Figure 3 is a broken elevational view with a part shown in cross section, taken along the line 45 III—III in Figure 2.

Figure 4 is an enlarged vertical cross-sectional view of another form of journal or bearing support for the table rolls according to this invention.

As shown on the drawing: 50
In Figure 1 the reference numeral 10 designates a Fourdrinier forming wire trained between a breast roll 11 and a couch roll 12. The upper run of the forming wire 10 is supported on 55

small diameter table rolls 13 disposed between the breast and couch rolls within the loop of the wire. The rolls 13 are journaled in bearing supports composed of members 14 and 15 surrounding the rolls 13 for more than 180° therearound, 5 but allowing the tops of the rolls to contact the under side of the upper run of the forming wire 10.

The bearing segments 14 have deflector lips 16 extending laterally therefrom adjacent the tops 10 of the rolls 13.

The bearing segments 14 and 15 are carried on transverse bars 17 which can be carried either from the side frames of the paper making machine, as is more fully described in my application 15 Serial No. 55,753, now Patent No. 2,111,833 above referred to, or from suction boxes as disclosed in my copending application Serial No. 80,762, now Patent No. 2,111,835.

As best shown in Figure 2 the transverse bars 20 17 have finger portions 17a of reduced width extending upwardly therefrom. The bearing segments 14 and 15 have tails or leg portions 14a and 15a fitted against the opposite faces of the fingers 17a.

Bolts 18 extend through the leg portions 14a and 15a of the segments 14 and 15 and through the fingers 17a of the bars 17. Heads 19 of the bolts 18 are countersunk in the legs 14a. The bolts 18 have threaded ends 20 in screw-thread 30 relation with the legs 15a.

As shown in Figure 3, the bolts having the heads 19 are disposed at spaced intervals across the entire length of the table roll bearings. These 35 bearings support the table rolls across the entire width of the forming wire so that the rolls are journaled under their entire supporting lengths and cannot bend or bow out of shape.

Since the bearings or journals are in two segments, the same can be adjusted toward and 40 away from each other to regulate the size of the journals at various points along the lengths of the rolls. It is obvious that a manipulation of the bolts 18 can draw the segments 14 and 15 together or space the same apart.

Spaces 21 are provided beneath the rolls 13 and above the fingers 17a of the bars 17. These 45 spaces are between the bearing segments 14 and 15 and provide passageways that may be supplied with a lubricating fluid such as water to lubricate the rolls 13.

The bearing segments 14 are positioned on the breast roll sides of the table rolls 13 and since the forming wire travels from the breast 50 roll 11 to the couch roll 12 along its upper run, the table rolls rotate in a clockwise direction. The bearing segments 14 are thus on the ascending side of the table rolls 13.

The deflector lips 16 forming part of the bearing segments 14 define flat surfaces 16a directly under the forming wire 10 and adjacent the tops of the rolls 13. These surfaces 16a may initially contact the under sides of the wire 10 due to a slight sagging of the wire between the rolls 13. However the rolls 13 actually support 55 the wire 10 and contact between the surfaces 16a and the under side of the wire only occurs during initial operation of the device since any sag of the wire between the rolls 13 will wear away the surfaces 16a. This wearing in of the lip 16 is desirable since it permits the surfaces 16a to be in as close position as possible with the under side of the wire 10 without actually supporting the wire. If a film or layer of white water is 60 formed on the under side of the wire the sur-

faces 16a will wipe this layer from the wire and will cause better drainage through the wire.

Since there is no drainage of water through the wire as the same passes over the surfaces 16a the ascending sides of the rolls 13 cannot throw water back through the wire. Furthermore since the rolls 13 are mounted in close relationship, water thrown laterally by a preceding roll is deflected downwardly by the lip 16 and cannot roll up through the wire. 10

In the modification shown in Figure 4, a transverse supporting bar 25 has an elongated passageway 26 extending throughout substantially the entire length of the bar in the center thereof. The passageway or groove 26 is open at the 15 top of the bar.

The top portion of the bar is recessed on both sides thereof as at 27 and 28 to define wall portions 29 and 30 of reduced thickness at the top of the bar. 20

Bearing segments 31 and 32 have tail or leg portions 31a and 32a seated in the recesses 27 and 28.

Resilient gaskets 33 are interposed between the tail or leg portions 31a and 32a and the respective 25 walls 29 and 30.

Bolts such as 34 extend through the walls 29 and 30 and the portions 31a and 32a of the bearing segments 31 and 32 to clamp the bearing segments to the top of the bar 25. These bolts are 30 spaced along the length of the bearing segments at desired intervals. The heads, such as 35, of the bolts are countersunk in the portions 31a of the bearing segments 31. The bolts also have threaded ends 36 tapped through the portions 32a of the bearing segments 32 in screw thread 35 relation with these portions. The bolts thus can be manipulated to adjust the bearing segments 31 and 32 around the table roll 13 and the resilient gaskets 33 permit a drawing of the segments 40 31 and 32 together. Likewise a loosening of the bolts permits the gaskets 33 to expand and space the bearing segments at any desired distance from the table rolls 13.

A passageway 38 is formed between the bearing segments 31 and 32 beneath the roll 13. This 45 passageway 38 is in communication with the groove or passageway 26 of the bar 25. Liquid can be supplied to the passageway 26 through an opening 39 at one end thereof for flowing upwardly through the passageway 26 and through the passageway 38 around the roll 13 to lubricate the roll or to float the roll in the segments. 50

The bearing segment 31 has a deflector lip 39 55 formed on the top thereof defining a flat surface 39a adjacent the top of the roller 13 on the ascending side of the roll.

From the above descriptions it should be understood that this invention relates to deflectors 60 formed adjacent the tops of small diameter table rolls on the ascending side of the rolls. These deflectors prevent the rolls from throwing or rolling up white water through the forming wire and thus prevent disruption of fiber arrangements 65 on the wire. The tops of the deflectors extend as close as possible to the wire contacting part of the rolls so as not to leave a gap between the lip and the line of contact of the wire on the roll. Such a gap is undesirable since lubricating 70 water on the ascending side of the roll might be ejected from the roll through the gap into the web on the wire.

The deflectors prevent water or liquid ejected tangentially by a preceding table roll from passing back through the wire. The lips or deflectors 75

do not support the wire but are immediately adjacent the tops of the rolls and may initially contact the under side of the wire by virtue of a slight sagging of the wire between the rolls. However 5 the top surfaces of the lips will rapidly wear away and will not be in contact with the under side of the wire for an appreciable length of time.

The table rolls can be made of metal such as stainless steel, Monel metal, brass or the like, or 10 can be made of a plastic composition such as "Micarta". If desired, metal table rolls can be rubber covered.

The bearing supports can be metal such as stainless steel, brass or Monel metal. Likewise 15 the supports can be made of a plastic composition such as "Micarta" or can be rubber lined.

A desirable adaptation of the invention includes "Micarta" table rolls mounted in brass, Monel metal or stainless steel bearing supports. 20 Other desired combinations are stainless steel, brass or Monel metal rolls mounted in "Micarta" or rubber lined bearing supports.

I am aware that many changes may be made and numerous details of construction may be 25 varied through a wide range without departing from the principles of this invention, and I, therefore, do not purpose limiting the patent granted hereon otherwise than necessitated by the prior art.

30 I claim as my invention:

1. In a paper making machine having a forming wire trained around a breast roll and a couch roll, a plurality of closely spaced parallel small diameter table rolls mounted under the upper run 35 of the forming wire between the breast roll and couch roll for supporting the wire and elongated journals rotatably supporting the rolls throughout substantially their entire length and extending for more than 180° around the rolls, the improvement which comprises an extension on each 40 journal on the breast roll side of the table roll, said extension curved around the roll almost to the top thereof and extending laterally outward from the top of the roll toward the breast roll to 45 a point spaced from the table roll but terminating short of the adjacent table roll journal, said extension defining a flat surface ahead of the table roll immediately under the wire that operates to stop drainage through the wire and to 50 wipe off films of liquid carried by the under side of the wire and said curved portion of the extension operating to prevent water on the roll from being thrown up against the wire.

2. In a paper making machine having a forming wire trained around a breast roll and a couch roll, a plurality of closely spaced parallel small diameter rolls mounted under the upper run of the forming wire between the breast and couch rolls for supporting the wire, and pairs of spaced opposed bearing segments defining open topped elongated journals rotatably supporting the table rolls throughout substantially their entire lengths and extending for more than 180° around the 5 table rolls, the improvement which comprises the provision of short bearing segments on the couch roll sides of the table rolls terminating in spaced relation beneath the forming wire to provide a 10 passageway for liquids draining through the wire and thrown from the descending table rolls and the provision of bearing segments on the breast roll sides of the table rolls curved around the rolls almost to the tops thereof and extending laterally outward from said stops of the rolls to 15 points terminating short of the adjacent journals for defining flat shelves ahead of the ascending sides of the table rolls to stop drainage through the wire, to wipe off films of liquid carried by the underside of the wire, and to prevent 20 water on the rolls from being thrown up against the wire.

3. A table roll structure for a paper making machine having a forming wire comprising an elongated supporting member adapted to be 30 mounted transversely under the upper run of a forming wire, a pair of elongated spaced opposed bearing segments carried by said supporting member defining together an open topped cylindrical journal, a table roll rotatably mounted in 35 said journal to support the wire, said bearing segment on the descending side of the roll extending around the roll above the axis thereof but terminating in spaced relation from the top of the roll to provide a passage under the wire for liquids thrown from the roll and draining through the wire and said bearing segment on the ascending side of the roll extending around the roll almost to the top thereof to form a bearing for the roll, said segment on the ascending side of the roll 40 also extending laterally outward to define a flat surface ahead of the roll immediately under the wire that is operative to stop drainage of liquids through the wire, to wipe off films of liquid on the under side of the wire without scraping the wire and to prevent the roll from throwing liquids through the wire.

EARL E. BERRY.
